UNITED STATES PATENT OFFICE

2,428,938

PROCESS OF MAKING SHOES WITH SAFETY
BOX TOES

Harry G. McMurray, Wakefield, Mass., assignor
to Safety Box Toe Company, Holliston, Mass.,
a corporation of Massachusetts

Application September 21, 1945, Serial No. 617,761

1 Claim. (Cl. 12—146)

1

This invention comprises an improved process of manufacturing a safety shoe having greater strength and better shoe-making characteristics than have been found heretofore in shoes of this type, by a series of steps which facilitate the shoe-making operations in general and avoid difficulties which have been heretofore encountered in manufacturing shoes of this special type. For example, the welt sewer has heretofore experienced a great deal of difficulty in breaking needles by striking the steel box toe. By the process of my invention this difficulty is substantially if not entirely avoided.

The strength of the steel box toe depends largely upon its having an adequate tie or strut in the shoe bottom between its curved sides. Heretofore the provision of a tie has caused objectionable bulk in the shoe bottom, interfering to some extent with the flexing of the shoe and making difficult the necessary shoemaking operations. These difficulties are avoided in accordance with the present invention by forming a metal box toe with a thin sheet steel tie.

I employ a regular leather welt insole of from six to seven irons thickness, channeled and stock-fitted in the conventional manner to present a lower surface having an upstanding sewing rib and canvas reinforcing. The insole, except at the toe, is cut to fit the contour of a last bottom, but the toe portion is formed to extend beyond the end of the last by an amount substantially equal to the thickness of the metal box toe with which the shoe is to be assembled. The toe portion of the insole is split to form two plies, layers, or sections of which the upper is smooth and flat, while the lower carries the usual sewing rib and reinforcing canvas. The length of the upper section is reduced to correspond with the length of the last employed, with the result that the lower section extends slightly beyond the end of the upper section.

The insole is now tacked to the last bottom in the conventional manner; the upper is then assembled on the last, pulled over, staple side lasted, and heel seat lasted, all in accordance with methods ordinarily employed and exactly as if no metal box toe were to be used.

After the heel seat lasting operation, the pulling over tacks at the tip of the shoe are removed to release the toe portion of the upper and lining, if a lining is used, so that they may be pulled back to expose the tip of the last. The operator may now fold back the lower section of the split insole to expose the smooth flat upper section and then place the metal box toe in position

upon the toe of the last but between the lining and the upper. That is to say, the box toe wipes in the lining over the upper insole section and holds it in place. The lower insole section is then turned back over the base flange and the tie of the metal box toe and secured. The next operation is to last the toe in conventional manner and proceed with normal shoemaking operations. The box toe is thus incorporated in the structure of the shoe without in any way interfering with the making of the shoe. The sewing rib and insole edge at the toe are so disposed with respect to the metal box toe that there is no danger of breaking weltting needles.

15 These and other features of the invention will be best understood and appreciated from the following description of a preferred manner in which it may be carried out, selected for purposes of illustration and shown in the accompanying drawing in which:

Fig. 1 is a view in perspective of an insole prepared in accordance with my invention.

Fig. 2 is a fragmentary view in perspective showing the upper and lining in pulled over condition on the last.

Fig. 3 is a view in perspective of a metal box toe.

Fig. 4 is a fragmentary view in perspective showing the metal box toe placed upon the last;

30 Fig. 5 is a fragmentary view in longitudinal cross-section of the toe portion of the lasted shoe, and

Fig. 6 is a corresponding fragmentary view in perspective.

35 The first step in the novel process of my invention consists in preparing an insole of the type shown in Fig. 1. As herein shown, but not necessarily, I employ a full length leather insole 10 rounded or died out to conventional contour 40 but so patterned that the edge of the toe portion will extend about $\frac{1}{16}$ " beyond the edge of the last to be employed in making the shoe. I now split in from the toe end of the insole 10 approximately to the tip line, the splitting operation forming the toe portion of the insole into two superposed sections or layers 13 and 14. The section 14 on the top of the insole 10 is to lie against the last bottom, and the next operation is to trim the toe edge of the section 14 until it coincides with the dimensions of the last, in normal fashion. The lower section 13 is not trimmed and therefore extends about $\frac{1}{16}$ " beyond the section 14 and the top of the last.

45 The insole 10 is then stock-fitted in the normal manner for welt insoles. That is to say, a chan-

nel is formed along its edge and a flap turned up to form an upstanding sewing rib 11. The inner face of the rib and the surface of the insole within the rib 11 is then covered with a ply 12 of gem duck or other suitable reinforcing material. The insole is now ready to be used in assembling the shoe.

The next operation is to tack the insole 10 to the bottom of a conventional last 15, and an upper 16 together with a lining 9 are assembled upon the last 15 in the usual manner. The assembled shoe is then placed in a pulling-over machine which draws the upper and lining tightly about the last 15 and drives holding tacks 17 at various places through the upper, lining, insole, and into the last 15. The shoe is then side lasted and heel seat lasted, both by conventional methods and equipment. The fact that the insole section 13 extends beyond the tip of the last 15 in no way interferes with pulling-over or lasting. It may be noted at this point that the tip of the upper section 14 is to be enclosed within the metal box toe and that the section 14 of the insole is made shorter than the complete ribbed section 13 in order to compensate for the thickness of the box toe and to bring the tip surface of the metal box toe into registration with the end of the ribbed tip section 13.

The pulling over tacks are now removed, the upper 16 is turned back from the top of the last, and the ribbed section 13 is folded back to expose the inner surface of the upper section 14. The lining 9 is transversely slashed opposite the rear end of the box toe so that the tip portion may be brought inside the box. Subsequently the metal box toe 18 is placed upon the toe of the last over the lining 9 and encloses the lining and the tip end of the ply 14, as suggested in Fig. 4.

In Fig. 3 is shown a metal box toe of sheet steel comprising a dome shaped portion 18 merging into an inturned base flange 19, the rear ends of which are connected by a flat tie bar 20. For the material of the box toe, sheet steel of from .04 to .05 inch may be conveniently used. Before this box toe is placed upon the toe of the last 15, the lining 9 is wiped or gathered in by hand over the surface of the upper section 14 and confined between the insole and the base flange 19 of the box toe.

After the box toe has been placed firmly in position upon the toe of the last as shown in Fig. 4, the insole section 13 is restored to its original position covering the metal box toe beneath it. Preferably the section 13 is cemented down. The upper 16 may be wiped into place in a bed lasting machine or toe lasting may be accomplished in any desired manner, the upper being brought to the rib 11 and secured in place, for example, by staples as shown in Fig. 6, or by anchor tacks and toe wire. When the section 13 is replaced it will be understood that its outer peripheral contour

coincides at the tip with the peripheral contour of the metal box toe, the latter being gauged in this position by the short tip of the smooth inner section 14 of the insole 10.

5 The shoe may now be completed by the conventional shoemaking operations exactly as if it contained no metal box toe. The thickness of the enclosed metal is approximately the same as that of heavy box toe material used in work shoes, 10 and its presence is no more conspicuous in the tip of the finished shoe. The upper 16 may be sewn with the welt to the rib 11 and the outsole layed and stitched, if the shoe is to be a welt shoe. McKay or Compo shoes may be manufactured in 15 general as above described, and in those cases the rib 11 of the outer insole section will be eliminated. The essential characteristic of my improvement is the employment of a split insole, and any of the standard shoemaking processes 20 may be carried out in this manner without being otherwise modified from conventional procedure.

It will be seen that I have thus made available 25 a new and improved process of making work shoes or other shoes having incorporated therein the safety feature of a metal box toe, accurately placed and securely incorporated in the shoe structure, all without requiring shoemaking operations which in any way interfere with the conventional stock fitting or making processes now 30 conventionally followed.

In my copending application Ser. No. 567,403, filed December 9, 1944, I have disclosed an alternative procedure for carrying out the broad process of my invention and have included in that 35 application a generic claim covering the process as herein disclosed.

Having thus disclosed my invention and described in detail a preferred embodiment thereof, I claim as new and desire to secure by Letters 40 Patent:

The process of shoemaking including the steps of tacking to a last bottom an insole having its toe portion split into two superposed sections, the section next to the last bottom being shorter than the outer section, folding back the outer section of the toe portion, placing a metal box toe having a flat tie bar on the toe of the last with its said tie bar overlying the short toe section of the insole, covering the base of the box toe by the outer long insole section, and lasting an upper to the full length insole thus presented.
